UNITED STATES PATENT OFFICE.

LOUIS A. CASGRAIN, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR OPERATING ON SHOE PARTS.

Application filed October 22, 1917, Serial No. 197,890. Renewed April 29, 1922. Serial No. 557,424.

To all whom it may concern:

Be it known that I, LOUIS A. CASGRAIN, a citizen of the United States, residing at Beverly, in the county of Essex and State 5 of Massachusetts, have invented certain Improvements in Machines for Operating on Shoe Parts, of which the following description, in connection with the accompanying drawings, is a specification, like reference 10 characters on the drawings indicating like parts in the several figures.

This invention relates to machines for operating on blanks for use in the manufacture of boots and shoes, particularly to machines for treating heels before they are attached to shoes. Although the invention, in its broader aspects, is applicable to the treatment of shoe blanks in general, such, for example, as blanks which are used for 20 parts of shoe bottoms, the invention is herein shown by way of exemplification as adapted for effecting operations similar to those performed by the machine disclosed in my prior co-pending application Serial No. 152,

25 391, filed March 3, 1917, in which is described and claimed an automatic machine organized to breast a heel by first removing a thick chip from the heel breast and then again treating the heel to remove a thin 30 chip or to make a finishing cut. By reason of the fact that these cuts are both made upon the heel by successive operations of a single knife more time is necessarily consumed in the heel breasting than is the case 35 where the heel is treated by a single cut.

It is an object of this invention to provide an improved automatic machine for breasting heels which will impart a roughing cut and a finishing cut to each heel, retaining in this and other respects important 40 advantages characteristic of the machine shown in the said application, but which will effect these successive operations upon a heel as rapidly as the heel breasting operation can be effected by machines of the 45 type which make a single cut only.

A feature of the invention consists in a work support and a plurality of cutting edges constructed and arranged for relative 50 reciprocatory movement in the same direction to cause the edges to act successively to remove material from a face of the work. Thus one cutting edge continues the action

of the other and the first action may be a roughing cut and the second a finishing cut. 55 As shown herein a heel is operated upon and the cutting edges act to remove material successively from the heel breast first by a roughing and then by a finishing cut. Obviously other shoe blanks or shoe bottom 60 parts may be similarly treated.

Another feature of the invention consists in a support for shoe bottom blanks arranged for movement from station to station and reciprocating stock removing cutters 65 operating to remove stock from the blank at each of the successive stations, the organization being such that the blank is presented to the second cutter in position to have further material removed from it. Preferably and as shown the stock removing cutters are relatively displaced to cause successive portions of stock to be removed from the blank while the position of the blank relatively to its support and the planes 70 of reciprocation of the cutters remain unchanged.

In the illustrated construction, the two cutting edges are shown as knives operated 80 by a single operating means and therefore a roughing cut is imparted to one heel by one knife while another heel is being given a finishing cut by another knife, the machine having a heel carrier co-operating with these knives and between which and the knives there is relative movement to effect successive operations of the knives upon the same portion of the heel. As shown herein, the carrier moves to bring a heel 85 first into the field of operation of one knife and then moves to bring the same heel into the field of operation of another knife.

In a machine such as that of my prior application above mentioned, in which one knife makes two cuts, the single edge may 90 become too dull to give a satisfactory finishing cut while it may still be capable of continuing to make satisfactory roughing cuts for some considerable time. When, however, as illustrated, a roughing cut and 100 a finishing cut are performed by two distinct knives, the roughing knife may remain serviceable for its purpose after it would possibly have become too dull for finishing, and the finishing knife, being reserved for 105 a comparatively light cut, may remain ser-

viceable for a longer time than if it were used also for the heavy roughing cut.

In another broad aspect, features of the invention are to be recognized in an organization including a series of tools such as cutting tools for performing distinct operations upon heel blanks or the like, with means for taking the blanks automatically from a source of supply such as a magazine and presenting them sequentially to the tools for their operation on the blanks. Preferably the blanks are successively presented by intermittent movement at a series of operating stations at each of which a tool is located and the tools operate simultaneously on separate heels and successively upon the same heel. In the illustrated embodiment of the invention the machine is provided with a plurality of heel carriers co-operating with a plurality of knives, the knives and carriers being constructed and arranged for relative movement to effect operation of one knife on a heel on one carrier and another knife on a heel on another carrier. Preferably, and as shown, two knives are provided which operate simultaneously upon heels on separate carriers, one knife removing a thick chip from one heel while the other knife removes a thin chip from the other heel, the carriers being then advanced so that the heel from which the thick chip was removed will be in position to be treated by the other knife and a thin chip removed, another heel on another carrier being presented for operation of the knife which removes a thick chip. Four such carriers are shown herein arranged in an endless series, although other numbers and arrangements of carriers may be provided without departing from the invention. In the construction shown, a heel is fed to one carrier while a heel on the second carrier is receiving a roughing cut, a heel on the third carrier is receiving a finishing cut, and a heel on the fourth carrier is being removed from the machine.

Still further features of the invention are to be recognized in an organization including a plurality of blank carriers preferably arranged for intermittent movement in a horizontal plane, a plurality of operating means located at various positions of rest of the carriers for operating upon the blanks, a magazine for blanks, and mechanism for transferring a blank from the magazine and locating the blank in predetermined position on each of the carriers as they are presented in turn. Preferably and as shown the transferring mechanism acts to orient the blank, that is, to predetermine its rotational position about a vertical axis passing through the blank, and also acts positively to predetermine its longitudinal position on the carrier.

Further features of the invention consist

in novel heel supplying mechanism co-operating with the heel carrying means and comprising a heel magazine, and heel feeding means, relatively constructed and arranged so that the magazine overhangs the carrying means and the lowermost heel in the magazine is positively pushed by the feeding means on to the carrier but only partially from beneath the stack of heels in the magazine, and the carrier then carries the heel to the breasting means. The heel being fed is, therefore, frictionally engaged by the heels above it during its movement to the carrier. The heel is consequently constantly under control and no opportunity is afforded for the heel to become misplaced relatively to the feeding means or the carrier. Preferably the heel is clamped to its carrier before the carrier moves the heel to the breasting means.

It is desirable, though not essential, that the heels in the stack be held from descent while the lowermost heel is being fed into the machine, and during the retraction of the feeding members, and a further feature of the invention consists in means having this function. In the construction shown herein the heel next to the lowermost one is forced against the far side of the magazine, thus enabling the heel next to the one at the bottom of the stack to sustain the weight of those above it while the mechanism referred to above feeds the bottom or lowermost heel to one of the carriers, clamps the heel on the carrier, moves the carrier and clamped heel from under the overhanging portion of the stack and allows the stack of heels to drop to bring the next heel in front of the feeding members. Preferably means is provided for positively sustaining one end of the heel next to the lowermost one.

A further feature of the invention consists in improved means for ejecting a heel from the machine after it has been operated upon and comprises means by which power to effect ejection of the heel is stored up while the heel is being operated upon by the machine and is released to effect ejection of the heel after the work upon it is completed. As shown herein, a spring is arranged to be engaged and put under tension by a heel when it is inserted in the machine, the spring being held under tension until the heel has been subjected to the successive cutting operations after which it is released and expels the heel from its carrier. Furthermore, contact of the heel with the spring, while it is being fed into the machine, acts to steady the heel and prevents lateral displacement of the heel on its carrier.

A further feature of the invention consists in an organization comprising means for holding a blank or heel in one of a series of movable carriers to which the heel is fed

- while the carrier is at rest, with means operated by movement of the carrier for releasing the holding means. As shown, the holding means is a clamp which acts independently of movement of the carrier to hold the blank or heel in the position in which it is presented to the carrier and during the successive operations thereon and is afterward released, for example, by movement of the carrier to permit removal of the heel, for example by the ejecting means above mentioned.

Considering the above noted clamping and ejecting mechanism more broadly, features of the invention are to be recognized in the combination of a blank support, means for presenting a blank on the support, means for moving the support through a plurality of positions at which operations are performed on the supported blank, together with a clamping member movable into engagement with the blank to hold it on the support and means situated at different positions on the support for controlling the engagement of the blank with the clamping member and its release therefrom.

While the invention is herein shown and described as embodied in a machine for breasting heels, it will be clearly apparent that the invention is not limited in its application to such a machine and that various features of the invention are adapted to embodiment in machines for other uses.

These and other features of the invention and various novel combinations will appear more fully from the following detailed description when read in connection with the accompanying drawings and will be pointed out in the appended claims.

In the drawings,

Fig. 1 is a side elevation of a machine embodying this invention;

Fig. 1^a is a detail of the cam shown in Fig. 1;

Fig. 2 is a sectional plan view taken on the line 2-2 of Fig. 1;

Fig. 3 is a sectional plan view taken on the line 3-3 Fig. 1, showing details of the table rotating and indexing mechanism;

Fig. 4 is a front view partly in section showing particularly the heel clamping mechanism; and

Fig. 5 is a detail view of mechanism shown in Fig. 4.

Referring to Fig. 1 of the drawings, the numeral 2 indicates the frame of the machine. In a part 4 bolted to the frame and in effect integral therewith is journaled a vertical shaft 6. This shaft carries a rotating table or spider 8 in which are mounted four heel carrying plates 10, 11, 13 and 15. Each of these plates or carriers is pivoted to the spider 8 near its outer end at 12 and at its rear end has a downwardly directed lug 14. The lugs 14 rest on a collar 16 threaded

on the shaft 6. The vertical position of the collar 16 on the shaft determines adjustably the relation of the upper surfaces of the carriers 10, 11, 13 and 15 to a horizontal plane. This adjustment of the carriers determines the angle between the breast face of the heel and its tread face when the breast end is cut off by vertically moving knives to be described.

On the shaft 6 below the frame 4 is pinned a four toothed ratchet plate 20 (Fig. 3) below which is rotatably mounted on the shaft 6 a lever 22 carrying at one end a pawl 24 engaging the teeth of the ratchet and at the other end being connected by a link 26 pivoted to a block 27 journaled in the upper end of an arm 28 (Fig. 1). The arm 28 is pinned to a rock shaft 30 journaled in the frame 2 and having pinned to its opposite end another arm 32 which carries a cam roll engaging a cam path 34 in the inner face of a wheel 36 to which power is applied to drive the machine. The cam path 34 will act through the mechanism described to rotate the plate 20 and the table 8 one-fourth of a revolution at each rotation of the wheel 36 as will be readily understood.

To maintain the table 8 exactly in the position into which it is brought by action of the pawl 24, an indexing pin 40 is provided which has a conical lower end adapted to engage similarly shaped holes 42 in the ratchet plate 20. In the position shown in Fig. 1, the pin 40 is held raised against a spring 44 by a bell crank lever pivoted at 46 and having one arm connected at 48 to the pin 40 and another arm 50 positioned to be engaged by the upper end of the arm 28. As the arm 28 is moved outwardly by its cam to cause rotation of the plate 20, the arm 50 is released, allowing the pin 40 to be depressed by its spring 44 toward the plate 20 but by reason of the cam shape of the end of the arm 50 the pin 40 is not allowed to engage the plate until the plate has moved enough to bring the adjacent hole 42 out of alignment with the pin. Therefore, the pin will rest on the upper surface of the plate 20 and snap into the next indexing hole 42 when the limit of the throw of the pawl 24 for a given movement thereof is reached, holding the plate indexed during the return movement of the pawl to engage the next tooth of the ratchet 20, and being released only when the end of that movement is approached.

Guided for vertical movement in the frame 2 is a "cross head" 60 shaped in cross section as shown in Fig. 2 which is reciprocated by a crank 62 (Fig. 1) on a shaft 64 which carries the drive wheel 36. The crank 62 is connected to the cross head 60 by a connecting rod 66.

The cross head 60 carries two breasting

knives 67, 68, shown in section in Fig. 2, one being in position to breast a heel on the carrier 11 and the other in position to breast, at the same time, a heel on the carrier 13. The knives 67, 68, are arranged at slightly different distances from the center of the shaft 6 so that while the knife 67 is effecting a first or roughing cut on a heel on the carrier 11 the knife 68 is effecting 10 a second or light finishing cut upon the heel on the carrier 13. In the next position of the table 8, the heel on the carrier 11 already breasted once will receive a finishing cut from the knife 68.

15 Mechanism is provided for feeding heels one by one from a stack of heels to the carriers 10, 11, 13 and 15. The magazine containing the stack of heels comprises vertically arranged angle bars 70, 72 for engaging 20 the corners of the heels at the breast ends. The bars 70, 72 are arranged for adjustment to accommodate heels of different widths by means of slots in horizontal projections 74 from the bars engaged by cap 25 screws 76. The curved sides of the heels near their opposite ends are engaged by cylindrical bars 78, 80 mounted on arms 82 which have split clamps 84 engaging posts 86 set in the frame 4. The clamps 84 provide 30 for adjustment of the bars 78, 80 for different sizes of heels and also for vertical adjustment of the bars 78, 80 on the posts 86 for different heights of heels. The magazine constitutes means for presenting a 35 heel in position to be fed to one of the carriers. The feeding means will now be described.

Beneath the bars 70, 72, and in position 40 to engage the lowermost heel of the stack, are arranged feeding fingers 90, 92, pivoted at 45 94, 96 respectively to a plate 98 and interconnected at 100 for equal and opposite movement. The heel engaging ends of the fingers 90, 92 are notched to engage the breast corners of the lowermost heel and may be set for heels of different widths by means of a thumb head 102 on a screw 104 extending loosely through an outward extension 93 on the finger 92 and threaded into a stud 105 mounted in a lug on an outward extension 91 of the finger 90.

50 The plate 98 upon which the feeding fingers 90, 92 are mounted is carried on a reciprocating slide 106 (Fig. 1). Relative adjustment between the slide 106 and the plate 98 for different lengths of heels is effected by a thumb head 108 on a rod 110 threaded into the slide 106 and having a flange 112 engaging a recess in the plate 98. The slide 106 is reciprocated positively by a link 114 connected to the slide and to one 55 arm 116 of a rock shaft 118 journaled in the frame 4 and having another arm 120, the end of which is bifurcated to embrace a block 122 pivoted to the cross head 60.

When the cross head descends, the slide 106 and feeding fingers 90, 92 will move inwardly of the machine and push the lowermost heel partially from beneath the stack and on to the adjacent heel carrier 10. It 70 will be noted (Fig. 1) that the heels in the magazine overhang the path of the carriers but that the greater portion of the heels rests on a plate 126, shown in Fig. 2, above which are the fingers 90, 92, and below 75 which the slide 106 and plate 98 travel. The outer end of the plate 126 is cut away to admit the pivots 94, 96 of the fingers during their inward movement.

Since the lowermost heel is pushed only 80 partially from beneath the stack, its front or breast portion is held frictionally by the weight of the heels in the stack, but enough of the heel projects so that a clamp, to be described, may engage the top face of the 85 heel and hold it upon the carrier as the carrier moves from beneath the stack. In this construction the heel is under control at all times and no chance is given for the heel to be knocked about by the quick action of 90 the feeding fingers and becoming misplaced upon the carrier before it is clamped in position. Since the feeding fingers engage both breast corners of the heel, it has no tendency to rotate in the plane of its tread 95 face while being pushed upon the carrier and should the heel be displaced rotationally in its own plane it will be engaged first by one of the fingers and turned until engaged by the other; thus its position of 100 orientation is determined. Control of the heel is further assisted by contact of one of the springs 150 with the end of the heel which tends to prevent lateral displacement 105 of that end of the heel while it is being pushed into the machine. The heel therefore is not only transferred positively by a movement of translation from presented position to a predetermined position in the machine but also the position of orientation 110 of the heel or the direction of its longitudinal median line is determined.

It is desirable, although not essential, that the stack of heels be held from descent while the fingers are pushing inwardly the lowermost heel and returning to their outer position.

Mechanism for this purpose is shown in Figs. 1 and 2. A vertical rock shaft 130 journaled in the frame 4 carries an arm 132 having a pointed projection 134 adapted to engage at times the heel in the stack next to the lowermost one and hold the stack of heels from descending in the magazine. The arm 132 is connected to the shaft 130 by a split clamp 136 to permit vertical adjustment of the projection 134 for different heights of heels. The shaft 130 is provided below the slide 106 with an arm 138 carrying a roll 139 which engages a cam 140 130

on the slide. When the parts are in the position shown in the drawings, the cam 140 presses on the roll 139 and rocks the shaft 130 to hold the projection 134 out of engagement with the heel. When the slide moves inwardly the roll 139 is released and the shaft 130 is rocked by a spring 142 (Fig. 2) to cause the projection to engage the heel next to the lowermost one to hold that heel and those above it from descent while the lowermost heel is being pushed over the carrier 10. At the inner end of each of the carriers 10, 11, 13, 15 is arranged a leaf spring 150 having its upper end slotted at 151 and secured by a cap screw 152 to a frame 154 secured to the vertical shaft 6. By means of the slots 151 and the screws 152 the springs may be adjusted vertically and in and out in the direction of the length of the heel, and are set so that they will be engaged by the heels pushed against them and compressed inwardly. By engagement with the end of the heel as it is pushed upon one of the carriers the attendant spring 150 frictionally holds that end of the heel from lateral movement until it is clamped upon the carrier.

It is necessary to hold the heels clamped against the carriers after their insertion to prevent their being thrust out by the compressed springs 150 and also to hold them firmly during the subsequent breasting operations performed upon them. For this purpose there is mounted for vertical movement over each of the carriers 10, 11, 13, 15, a plunger 160. The plungers are all similar in construction and are splined to prevent rotation of them in their mountings. The portions of the frame 154 which guide the plungers for their vertical movement are recessed to accommodate collars 162 clamped to the plungers and between each collar 162 and an adjustable sleeve 165 threaded into the upper portion of the guiding frame 154

(Fig. 4) is a stiff spring 164, and on the lower end of each plunger 160 is a clamping plate 166 which is forced against the heel, when permitted to do so, by its spring 164. During this movement, the roll 170 passes off the projection 188 and the slide 182 is returned by its spring 186 to raised position against a stop 181 where it is again locked as soon as the cross head 60 starts to ascend and before the roll 170 of the next plunger arrives over it.

The plunger at the left of Fig. 1 is shown in clamping position holding a heel on the carrier 13. The collars 162 engage the frame 154 to prevent excess movement of the plungers when no heels are under them. When each carrier 10, 11, 13, 15 reaches the position of carrier 15 in Fig. 1, it is necessary to release the clamping plate 166 and allow the heel to be ejected by reaction of the compressed spring 150. To effect this, the collars 162 are provided with rolls 170 which ride on a stationary cam 172 mounted on a depending portion 174 of the frame 2. The rise of the cam 172 is shown in Fig. 1 as acting when the carrier 13 passes to the position of carrier 15.

The clamp 166 over the carrier 10 should be held raised as shown in Fig. 1 until the heel is inserted beneath it and should then be allowed to descend to hold the heel before it is moved to the next position where it is breasted. Thus to operate the clamp, mechanism best shown in Figs. 4 and 5 is provided. Referring to Fig. 4, the depending portion 174 of the frame is provided with ways 180 in which a slotted slide 182 is guided. The slot of the slide 182 embraces a fixed block 184 connected by a tension spring 186 to the lower portion of the slide 182. On the lower end of the slide 182 is an outwardly extending projection 188, the upper face of which, when in the position shown, forms a continuation of the acting face of the cam 172. The roll 170 of the plunger which is over the carrier in the position of the carrier 10 rests on the projection 188, the slide and projection being at that time upheld by a latch 190 which engages a projection on the upper end of the slide 182, as shown in Fig. 5. The latch 190 is pivoted to the part 174 at 192 and is held in latching position by a spring 194. On the latch 190 is an arm 196 which is engaged by one end of an unlatching lever 198 pivoted at 200 to the frame 2 and carrying at its opposite end a slotted link 202. In the slot of the link 202 is arranged a pin 204 extending between lugs 206 on the cross head 60. When the cross head descends, the pin 204 engages the end of the slot in the link 202 and operates the lever 198 to release the latch 190, allowing the slide 182 and projection 188 to descend under the impulse of the plunger spring 164 which overcomes the weaker spring 186, the clamp 166 on the plunger then engaging the heel on the carrier 10 while the carrier travels to the shown position of the carrier 11 and under the first 105

breasting knife 67.

During this movement, the roll 170 passes off the projection 188 and the slide 182 is returned by its spring 186 to raised position against a stop 181 where it is again locked as soon as the cross head 60 starts to ascend and before the roll 170 of the next plunger arrives over it.

The mechanism of the machine has now been sufficiently described so that its operation will readily be understood, and such a description will now be given with reference to the passage of a single heel through the machine, it being understood that a similar operation is performed upon each heel as 115 heels are fed in turn to the carriers 10, 11 13 and 15. Supposing the magazine 70, 72, 78, 80 to be filled with heels and the machine started. The cross head 60 begins to descend and the block 122, through the connections described, operates the slide 106 to carry the fingers 90, 92 against the lowermost heel in the stack and push it inwardly over the carrier 10 and against the spring 150. Early in the same movement, the cam 130

140 allows the spring 142 to force the point 134 against the heel next to the lowermost one, thereby pushing it against the inner guides 78, 80 of the magazine and holding 5 up the stack of heels above it until the fingers are again retracted, whereupon the point 134 is withdrawn and the stack of heels drops to bring the next heel in front of the fingers 90, 92. During the descent of 10 the cross head 60, the pin 204 hits the end of the slot in the link 202, operating the lever 198 to unlatch the slide 182 and allow the spring 164 of the plunger over the carrier 10 to operate and clamp the heel 15 upon the carrier 10. During the return of the cross head the table 8 is rotated by the means described one-fourth of a revolution, and the heel clamped on the carrier 10 is brought under the knife 67 which, upon the 20 next descent of the cross head 60, removes a thick chip from the breast end of the heel as the first or roughing cut. The cross head again ascends and the heel is brought to the third position under the second breast- 25 ing knife 68, where, upon the next descent of the cross head, a thin finishing chip is removed from the breast. Upon the next ascent of the cross head, the heel is moved to its fourth position, during which movement the roll 170 engages the rise of the cam 172, which unclamps the heel and allows the spring 150 behind the heel to react and eject the heel from the machine. It will be understood, of course, that in the 30 meantime heels have been fed in turn to the carriers 11, 13 and 15, and that while one heel is receiving a rough cut by the knife 67 another heel is receiving a finishing cut by the knife 68 so that there is no loss of 35 time as in my prior machines where a single knife makes successive cuts upon the same heel.

Having fully described my invention, what I claim as new and desire to secure by 45 Letters Patent of the United States is:—

1. In a machine of the class described, a horizontally arranged rotary carrier for heels, means for breasting one heel on the carrier, means for breasting another heel on 50 the carrier at the same time, and means for relatively operating the carrier and breasting means in timed relation.

2. In a machine of the class described, means for treating one heel to a first breasting operation, and means for treating the 55 same portion of another heel at the same time to a second breasting operation.

3. In a machine of the class described, two reciprocating knives having different locations, and means for moving a heel to present it first to one knife and then to another knife for successive operations of the knives upon the heel.

4. In a machine of the class described, 60 two breasting knives having different loca-

tions, and means for presenting a heel first to one knife in one location and then moving the heel to another knife in another location for successive operations of the knives upon the breast face of the heel.

5. In a machine of the class described, two breasting knives having different locations in the machine, and means for moving a heel to present it to one knife for a roughing cut upon the heel breast and then moving the heel to present the heel to the other knife for a finishing cut.

6. In a machine of the class described, two reciprocating knives, and means for presenting a heel to one knife for a roughing cut and then by movement of the heel presenting it to the other knife for a finishing cut upon the same portion of the heel treated by the first knife.

7. In a machine of the class described, two knives, and means for presenting a heel to one knife for a roughing cut upon its breast face and then to the other knife for a finishing cut coextensive with the first cut upon the same face of the heel to form a smooth breast.

8. In a machine of the class described, the combination of a first breasting knife, a second breasting knife, means for presenting a shoe heel to the first knife and then to the second knife, and means for presenting a second heel to the first knife at substantially the same time the first heel is presented to the second knife.

9. In a machine of the class described, the combination of a first knife and a second knife, means for presenting a shoe heel to the first knife to breast the heel and then to the second knife to finish the heel breast, and means for presenting at the same time 100 a second heel to the first knife to breast the second heel.

10. In a machine of the class described, the combination of a plurality of knives, a carrier for an unattached heel, and means 110 for effecting relative movements between the knives and carrier successively in the same direction to effect successive operations of the knives on the heel on the carrier.

11. In a machine of the class described, the combination of a plurality of the breasting knives, a carrier for an unattached heel, and means for effecting relative movements in the same direction between the knives and carrier to effect successive operations of the knives on the breast of the heel on the carrier.

12. In a machine of the class described, the combination of a plurality of similar knives operating in the same direction, a 115 heel carrier, and means for operating the carrier to present the heel for the operation of the knives in succession upon the heel.

13. In a machine of the class described, the combination of a plurality of similarly 120

- shaped knives, a heel carrier, and means for operating the carrier to present the heel for the operation of the knives to remove successive chips from the entire surface of the heel breast. 5
14. In a machine of the class described, a plurality of similar reciprocating knives, a plurality of heel carriers between which and the knives there is relative movement to bring the heel carriers successively into operative relation to the knives, and means for moving relatively the knives and carriers to effect operation of the knives upon the heels on the carriers. 10
15. In a machine of the class described, a plurality of breasting knives, a plurality of heel carriers, and means for moving relatively the knives and carriers to effect successive breasting operations of the knives, upon each heel on the carriers. 15
16. In a machine of the class described, a plurality of reciprocating knives, a plurality of heel carriers, and means for moving relatively the knives and carriers to effect successive operations of the knives upon the heels on the carriers and simultaneous operation of knives on the heels carried upon adjacent carriers. 20
17. In a machine of the class described, a plurality of knives, a plurality of heel carriers, and means for moving relatively the knives and carriers to effect successive breasting operations of the knives upon the heels on the carriers and simultaneous operation of knives on the heels carried upon adjacent carriers, one heel receiving a roughing cut while the other receives a finishing cut. 25
18. In a machine of the class described, the combination of heel carriers for unattached heels arranged in an endless series, means for intermittently moving the series, and a plurality of reciprocating knives arranged to operate upon separate heels on the carriers while they are at rest. 30
19. In a machine of the class described, the combination of heel carriers arranged in an endless series, and a plurality of breasting knives arranged to operate simultaneously upon separate heels upon separate carriers. 35
20. In a machine of the class described, the combination of heel carriers arranged in an endless series, and a plurality of breasting knives arranged to operate upon separate heels on the carriers, the series being movable to present a given heel on a carrier for operation of the knives in succession on that heel. 40
21. A heel breasting machine organized and operated automatically to breast heels comprising, in combination, an intermittently operated heel carrying table, means for presenting heels in feeding position, means for positively feeding heels one by one to a predetermined position on the table, means for holding the heels on the table, means for breasting the heels, and means for releasing the heels. 45
22. A heel breasting machine organized and operated automatically to breast heels comprising, in combination, an endless intermittently operated heel conveyor, means located at one point in the travel of the conveyor for transferring a heel to the conveyor, means for holding the heel on the conveyor, means operating at another point to breast the heel, and means operating at still another point for releasing the heel holding means. 50
23. In a machine of the class described, a plurality of heel carriers arranged in an endless series, knives arranged to operate at the same time upon separate heels on separate carriers, and means for inserting a heel on another carrier while the first mentioned carriers are located in operative relation to the knives. 55
24. In a machine of the class described, a plurality of heel carriers arranged in an endless series, knives arranged to operate at the same time upon separate heels on separate carriers, and means for simultaneously inserting a heel on another carrier. 60
25. In a machine of the class described, a plurality of heel carriers arranged in an endless series, knives arranged to operate at the same time upon separate heels on separate carriers, means for inserting a heel upon another carrier while the first mentioned carriers are located in operative relation to the knives, and means for ejecting a heel from a fourth carrier. 65
26. In a machine of the class described, a plurality of heel carriers arranged in an endless series for movement in a horizontal plane, a knife arranged for vertical reciprocation to operate upon a heel on one of the carriers, means for positively inserting a heel in predetermined position upon another carrier while the first mentioned carrier is located in operative relation to the knife, and means for releasing a heel from another carrier located beyond the knife. 70
27. In a machine of the class described, a plurality of heel carriers arranged in an endless series, knives arranged to operate upon separate heels upon separate carriers, means for inserting a heel upon a carrier in advance of those containing heels upon which the knives are operating, and means for ejecting a heel from a carrier beyond those upon which heels are being treated by the knives. 75
28. In a machine of the class described, the combination of a plurality of heel carriers for unattached heels, arranged in an endless series, a plurality of breasting knives and means for moving and holding the carriers in operative relation to the knives and 80

in position for one knife to operate upon a heel on one carrier and another knife upon a heel on another carrier.

29. In a machine of the class described, 5 the combination of a plurality of heel carriers for unattached heels arranged in an endless series, a plurality of reciprocating knives, means for moving and holding the carriers in operative relation to the knives
- 10 and in position for one knife to operate upon a heel on one carrier and another knife upon a heel on another carrier, and means for reciprocating the knives in each position of the carrier.
- 15 30. In a machine of the class described, the combination of a plurality of heel carriers for unattached heels arranged in an endless series, a plurality of knives, and means for moving and holding the carriers 20 in operative relation to the knives and in position for one knife to operate upon a heel on one carrier and another knife upon a heel on another carrier, the knife which operates upon one heel operating upon the 25 next heel in the next position of the carriers.
31. In a machine of the class described, the combination of a plurality of heel carriers arranged for movement about a center, a plurality of knives arranged at different 30 distances from said center, and means for moving and holding the carriers in operative relation to the knives and in position for one knife to operate upon a heel on one carrier and another knife upon a heel on another 35 carrier, the knife which operates upon one heel operating upon another heel in another position of the carriers.
32. In a machine of the class described, the combination of a magazine adapted to 40 contain heels, an endless series of carriers mounted to be moved in a plane below the magazine with a portion of the lowermost heel projecting over the path of the carriers, means for moving the lowermost heel in 45 the magazine completely over one of the carriers and partially from beneath the magazine, means for clamping the exposed portion of the heel upon the carrier while it is under the magazine, means for moving 50 the carriers to transport the heels, and means for breasting the heels while they are being transported by the carriers.
33. In a machine of the class described, the combination of a magazine adapted to 55 contain heels, a series of carriers mounted to be moved in a plane below the magazine with a portion of the lowermost heel projecting over the path of the carriers, means for moving the lowermost heel in the 60 magazine completely over a carrier and partially from beneath the magazine, means for moving the carriers to transport the heels, and means for operating upon the heels while they are being transported by the carriers.
34. In a machine of the class described, the combination of a magazine, a series of carriers arranged adjacent to one end of the stack of heels in the magazine, means for positively pushing out one heel at a time 70 from the stack into predetermined position on a carrier, means for clamping the heel, and means operating to breast the heel at another position of the carriers.
35. In a machine of the class described, 75 the combination of a magazine, a series of carriers arranged adjacent to one end of the stack of heels in the magazine, means for positively feeding one heel at a time from the stack into predetermined position on a 80 carrier, and means operating to breast the heel at another position of the carriers.
36. In a machine of the class described, the combination of a magazine, a carrier arranged for movement in a path which partially underlies the stack of heels in the magazine, and means for pushing the lowermost heel in the magazine into position on the carrier and partially from beneath the stack. 85
37. In a machine of the class described, the combination of a magazine, a series of heel carriers arranged for movement in a path which partially underlies the stack of heels in the magazine, and means for pushing the lowermost heel in the magazine into 90 position on a carrier and partially from beneath the stack.
38. In a machine of the class described, the combination of a magazine, a series of 100 heel carriers arranged for movement in a path which partially underlies the stack of heels in the magazine, means for pushing the lowermost heel in the magazine into position on a carrier and partially from beneath the stack, means for clamping the heel to the carrier, and means acting subsequently to breast the heel. 105
39. In a machine of the class described, the combination of a magazine for presenting 110 a heel in position to be fed, a series of heel carriers arranged for movement in a path adjacent to the presenting means, means for positively feeding the presented heel into predetermined position on a carrier, means for clamping the heel to the carrier, and means for breasting the heel on the carrier. 115
40. In a machine of the class described, the combination of a magazine to contain 120 heels, a series of heel carriers arranged for movement in a plane below the magazine, means for positively pushing the lowermost heel in the stack into predetermined position upon a carrier, and heel breasting means acting subsequently to breast the heel on 125 the carrier.
41. In a machine of the class described, the combination of means for presenting a heel in position to be fed, a series of heel carriers arranged for movement past the 130

- presenting means, means for positively feeding the presented heel into predetermined position upon a carrier, and heel breasting means acting in a subsequent position of the carrier to breast the heel on the carrier.
42. In a machine of the class described, the combination of a magazine to contain a stack of heels, a series of heel carriers arranged for movement in a plane below the magazine, means for engaging and transferring the lowermost heel in the stack out of the stack into position upon a carrier, and means for sustaining the stack of heels during the action of the feeding means.
43. In a machine of the class described, the combination of a magazine to contain a stack of heels, a series of heel carriers arranged for movement in a plane below the magazine, means for transferring the lowermost heel in the stack from the stack into position upon a carrier, and means operating after movement of the transferring means begins for positively sustaining the stack of heels during the action of the transferring means.
44. In a machine of the class described, the combination of a magazine to contain heels, a series of heel carriers arranged for movement in a plane below the magazine, means for pushing the lowermost heel in the stack into position upon a carrier, means for sustaining the stack of heels for the action of the pushing means, and heel breasting means acting subsequently to breast the heels upon the carrier.
45. In a machine of the class described, the combination of a magazine to contain heels, a series of heel carriers arranged for movement in a plane below the magazine, means for feeding heels singly from the stack to the carriers, means for sustaining the heels in the stack above the heel being fed during the retraction of the feeding means, and means acting subsequently to breast the heel.
46. In a machine of the class described, the combination of a magazine to contain a stack of heels, a series of heel carriers arranged for step by step movement past the magazine, means for feeding heels from the stack to the carriers, means for sustaining the heels in the magazine above the heel being fed during the retraction of the feeding means, and means acting at a subsequent step in the movement of the carriers to breast the heel.
47. In a machine of the class described, means for breasting one heel, means for breasting another heel at the same time, and mechanism to cause the first heel to be acted upon by the second breasting means in a subsequent operation.
48. In a machine of the class described, the combination of a magazine to contain heels, a series of heel carriers arranged for movement in a plane below the magazine, means for forcing the heel in the magazine which is next to the lowermost heel against one side of the magazine to sustain the heels above it, and means for feeding the lowermost heel into operative position upon a carrier.
49. In a machine of the class described, the combination of a magazine to contain heels, a series of heel carriers arranged for movement in a plane below the magazine, means for forcing the heel in the magazine which is next to the lowermost heel against one side of the magazine to sustain the heels above it, means for feeding the lowermost heel into position upon a carrier, and means acting subsequently to breast the heel.
50. In a machine of the class described, the combination of a magazine to contain a stack of heels, a heel carrier arranged for movement past the magazine, means for feeding the lowermost heel in the stack into position upon the carrier, and means for forcing the heel in the stack which is next to the lowermost heel against one side of the magazine to sustain the heels above it while the lowermost heel is being fed.
51. In a machine of the class described, the combination of a magazine to contain heels, a series of heel carriers arranged for movement in a plane below the magazine, means for positively engaging one end of the heel in the stack which is next to the lowermost heel to sustain that end of the heel, means for feeding the lowermost heel into position upon a carrier, and means acting subsequently to breast the heel.
52. In a machine of the class described, the combination of a magazine to contain heels, a heel carrier arranged for movement past the magazine, a pointed projection for engaging one end of the heel in the stack which is next to the lowermost heel to sustain that end of the heel, and means for feeding the lowermost heel into position upon the carrier.
53. In a machine of the class described, the combination of a magazine to contain heels, a series of heel carriers arranged for movement in a plane below the magazine, means for feeding the lowermost heel in the magazine to a carrier, means responsive to movement of the feeding means for sustaining the stack of heels in the magazine above the heel being fed, and means acting subsequently to breast the heel.
54. In a machine of the class described, the combination of a magazine to contain heels, a carrier arranged for movement past the magazine, means for controllably feeding a heel from the magazine to a position on the carrier, and means responsive to movement of the feeding means for sustaining the heels in the magazine above the heel being fed.

55. In a machine of the class described, the combination of a magazine to contain heels, a series of heel carriers arranged for movement in a plane below the magazine, 5 a pusher for pushing the lowermost heel in the stack to one of the carriers, means responsive to the feeding movement of the pusher for sustaining the heels above the lowermost heel in the stack, means for releasing the heels and permitting them to descend in the magazine, and means acting subsequently to breast the heel fed to the carrier.
56. In a machine of the class described, 15 the combination of a magazine to contain heels, a carrier arranged for movement in a plane below the magazine, a pusher for pushing the lowermost heel in the stack to the carrier, and means responsive to the feeding movement of the pusher for sustaining the heels above the lowermost heel in the stack, and for releasing the heels and permitting them to descend in the magazine after feeding movement of the pusher.
57. In a machine of the class described, 25 the combination of a magazine for containing heels, a series of heel carriers arranged for movement in a plane below the magazine, means for feeding the heels to the carriers in succession, means for breasting the heels while on the carriers, means energized by insertion of the heel for expelling the heels from the carriers, means for preventing operation of the expelling means during the breasting operation, and means for releasing the expelling means after the heels are breasted.
58. In a machine of the class described, 35 the combination of means for presenting heels to be fed to the machine, heel carriers arranged for movement past the presenting means, means for feeding the heels to the carriers in succession, means for operating upon the heels while on the carriers, means tensioned by the feeding means for expelling the heels from the carriers, means for preventing operation of the expelling means during the operation upon the heels, and means for releasing the expelling means after the heels are operated upon.
59. In a machine of the class described, 45 the combination of a heel carrier, means for feeding a heel to the carrier, means operated by introduction of the heel into the carrier for storing energy to effect expulsion of the heel, and means for releasing that energy to expel the heel from the carrier.
60. In a machine of the class described, 55 the combination of a series of heel carriers arranged for movement in a plane below the magazine, means for feeding the heels to the carriers in succession, means for breasting the heels while on the carriers, means operated by introduction of the heels in the carriers for storing energy to effect expulsion of the heels, and means for releasing that energy after the heels are breasted to expel the heels from the carriers.
61. In a machine of the class described, 65 the combination of a magazine, a series of heel carriers arranged for movement past the magazine, means for feeding the heels from the magazine to the carriers in succession, means for operating upon the heels while on the carriers, ejecting springs placed under tension by introduction of the heels into the carriers, means for holding the springs under tension until the heels are operated upon, and means for then releasing the springs to expel the heels from the carriers.
62. In a machine of the class described, 75 the combination of a magazine to contain heels, a heel carrier arranged for movement past the magazine, means for feeding a heel from the magazine to the carrier, means independent of movement of the carrier for clamping the heel, and means operated by movement of the carrier for releasing the clamping means.
63. In a machine of the class described, 85 the combination of a magazine to contain heels, a series of heel carriers arranged for movement past the magazine, means for feeding heels from the magazine to the carriers, means independent of movement of the carriers for clamping the heels, and means operated by movement of the carriers for releasing the clamping means.
64. In a machine of the class described, 95 the combination of a series of heel carriers arranged for movement past a feeding point, means for feeding heels to the carriers, means for breasting the heels, means rendered operative by the breasting means for clamping the heels, and means operated by movement of the carriers for releasing the clamping means.
65. In a machine of the class described, 105 the combination of a magazine to contain heels, a series of heel carriers arranged for movement past the magazine, means for feeding a heel to each carrier as it passes the magazine, means for breasting the heels at another position of the carriers, means responsive to movement of the breasting means for clamping the heels upon the carriers, and means responsive to movement of the carriers for releasing the heels after the breasting operation.
66. In a machine of the class described, 115 the combination of a magazine to contain heels, a heel carrier arranged for movement past the magazine, means for feeding a heel to the carrier as it passes the magazine, means for breasting the heel at another position of the carrier, means responsive to movement of the breasting means for clamping the heel upon the carrier, and means responsive to movement of the carrier for re-

leasing the heel after the breasting operation.

67. In a machine of the class described, the combination of a stationary magazine to contain heels, a feed slide arranged to push the lowermost heel out of the magazine, a prick point held out of contact with the heels when the feed slide is retracted, and resilient means for forcing the prick point 10 against the heel next to the lowermost heel during the operation of the feed slide.

68. In a machine of the class described, the combination of a stationary magazine to contain heels, means acting on the lowest heel in the magazine to eject that heel from the magazine, and means for pressing the next heel above the rejected heel against a wall of the magazine during the ejecting operation.

69. A machine of the class described having, in combination, a breasting knife, a carrier to which heels are fed for transference to the knife, a series of spring operated clamps for holding the heels on the carrier, 25 a cam for raising the clamps in succession, a slide located in the cam path for controlling whichever one of the clamps is transferred to the feeding point, and means operated by the knife for releasing the slide 30 to allow the clamp to clamp the heel.

70. A machine of the class described having, in combination, a breasting knife, a carrier to which heels are fed for transference to the knife, a series of spring operated 35 clamps for holding the heels on the carrier, a cam for raising the clamps in succession, a slide located in the cam path into control of which slide one of the clamps is transferred at the feeding point, means operated 40 by the knife for releasing the slide to allow the clamp to clamp the heel, and means for restoring the slide to normal position.

71. In a machine of the class described, the combination of a rotating carrier, means 45 for imparting to the carrier intermittent partial rotations, an indexing plate secured to the carrier and having a plurality of openings, a spring pressed indexing pin adapted to engage the openings in succession to hold the carrier in indexed position, and means for lifting the indexing pin and releasing it while the plate is in motion to cause the pin to rest on the plate and snap into the next hole when the partial rotation 50 of the plate has been effected.

72. In a machine of the class described, the combination of a rotatable table, a plurality of carriers attached to the table for movement about pivots located near one end 60 of each carrier, and a single means engaging the opposite ends of all of the carriers arranged for adjustment to vary the angular disposition of the carriers relatively to the plane of the table.

73. In a machine of the class described,

the combination of an intermittently rotating table having heel carriers, and automatic means for transferring to each of the carriers in succession a single heel and locating it thereon in predetermined position, 70 breasting the heels and delivering the heels from the machine.

74. In a machine for handling and breasting heels automatically, the combination of a series of heel carriers arranged for movement past a feeding point, means for transferring heels at the feeding point to the carriers, means acting independently of the carrier movement for holding the heels on the carriers, means for breasting the heels, 75 and means operated by movement of the carriers for releasing the heels.

75. A machine for operating upon unattached shoe heels having, in combination, an intermittently operated carrier, heel breast- 85 ing means, means for presenting and positively locating heels in the carrier, and means for moving the carrier to present heels to the breasting means and to remove the heels from the breasting means after 90 the breasting operation.

76. A machine for breasting unattached heels having, in combination, a breasting tool, a series of intermittently operated heel carriers, and mechanism operating automatically to present heels in succession in predetermined position on the carriers, to hold the heels in the carriers, to relatively 95 operate the carriers and breasting tool to effect breasting operations upon the heels in 100 succession during periods of rest of the carriers, and to release the heels from the carriers.

77. In a heel breasting machine, the combination of breasting means comprising a 105 plurality of cutting edges, a heel support, means for effecting relative movement between the support and the breasting means to cause relative reciprocation heightwise of the heel and to cause one of the cutting 110 edges to continue the action of the other on the heel breast.

78. A heel breasting machine having, in combination, breasting means, a heel support, means for moving the heel support from station to station in the machine, and means for causing the breasting means to 115 perform a breasting operation on the same heel at a plurality of stations.

79. In a heel breasting machine, the combination of breasting means, a heel support, means for effecting relative reciprocatory movement between the breasting and the support to produce the breasting stroke, said parts being constructed and arranged to cause the breasting operation to be repeated on each heel on the support without relative movement of the breasting means and heel lengthwise of the heel.

80. In a machine of the class described, 120

the combination of a plurality of knives, a heel support, and means for relatively operating the support and knives to cause the knives to remove chips in succession from 5 the entire surface of the heel breast.

81. In a heel breasting machine, the combination of breasting means comprising a plurality of cutting edges, a heel support, and means for effecting automatically relative movement between the breasting means 10 and the support to cause one of said cutting edges to operate and then the other to repeat the operation of the first cutting edge on the heel.

82. In a heel breasting machine, the combination of breasting means comprising a plurality of cutting edges, a heel support, and means for effecting relative rectilinear reciprocation between the breasting means 20 and the support to cause one of said cutting edges to breast the heel and the other to treat the surface formed by the first cutting edge to a finishing cut.

83. In a machine for operating on shoe parts, the combination of cutting means comprising a plurality of cutting edges, a work support, means for effecting relative movement between the support and the cutting means to cause relative reciprocation 30 substantially perpendicularly to the support and to cause one of the cutting edges to continue the action of the other.

84. In a machine for treating blanks, operating mechanism, an intermittently rotatable turret for presenting the blanks to the operating mechanism, a movable clamping member for securing the blanks to the turret, and power operated means arranged for operation in timed relation to the movements of said operating mechanism for actuating the clamping member when the turret is stopped.

85. In a machine for operating on shoe parts, the combination of stock removing means, a work support, means for effecting relative reciprocatory movement between the operating means and the support to cause the operating means to treat the part on the support, said means and support being constructed and arranged to cause the operation of the operating means to be repeated on the same face of each part on the support while the part remains in the same position relatively to the support and the plane of relative reciprocation between the operating means and the support is unchanged.

86. In a machine of the class described, a pair of cutting edges, a heel support, and automatic means constructed and arranged to effect relative movement between the support and the cutting edges in a plane substantially parallel to the plane of the heel breast to cause the two edges to act successively upon the heel, one to breast the heel

and the other to remove a further portion of the heel breast formed by the first.

87. In a machine of the class described, the combination of an intermittently operated endless carrier for heels, and automatic means for transferring heels in predetermined position one by one to the carrier in succession, breasting the heel and delivering the heel. 70

88. In a machine of the class described, 75 the combination of an intermittently operated endless series of heel carriers and automatic means for transferring to each of the carriers a single heel and locating it thereon in predetermined position, clamping 80 the heel, breasting the heel and delivering it from the machine.

89. In a machine of the class described, the combination of a heel support, means engaging the opposite ends of the breast 85 face of the heel, means for effecting positive relative movement between the support and heel to cause the heel to be positioned on the support in predetermined position, and means for breasting the heel so positioned. 90

90. In a machine for treating heels, the combination of a support, heel feeding means positively actuated to engage the breast end of the heel and move the heel into predetermined position on the support, 95 and means engaging the opposite end of the heel for yieldingly resisting movement of the heel to maintain contact of the heel with the feeding means.

91. In a machine for treating heels, the 100 combination of a heel support, positioning means engaging the opposite ends of the heel breast face, yielding positioning means engaging the rear end of the heel, and means for operating the breast engaging means substantially positively to cause the heel to be fed and located in predetermined position on the support. 105

92. In a machine for operating on shoe heels, heel treating means requiring location of the heel relatively to it in predetermined position in the plane of the tread face of the heel both as to translation and orientation, positioning means engaging the breast end of the heel at two separated 110 points to determine the orientation of the heel, means engaging the rounded end of the heel for yieldingly opposing movement of the heel and means for positively operating one of the positioning means to translate the heel. 115

93. In a machine for treating heels, the combination of a support, yielding means on the support to be engaged by the end of a heel, heel feeding means positively actuated to engage the opposite end of the heel and move the heel against the yielding means into predetermined position on the support, and means for clamping the heel while so positioned. 125 130

94. In a machine for treating heels, the combination of a heel support, positioning means engaging the side portions of the heel breast face, positioning means engaging the rear end of the heel, means for holding one of said positioning means yieldingly, means for operating the other positioning means substantially positively to cause the heel to be fed and located in predetermined position by said positioning means, and means for clamping the positioned heel to the support.

95. In a machine for operating on shoe blanks, blank treating means requiring location of the blank relatively to it in predetermined position in the plane of the blank both as to translation and orientation, relatively operated positioning means one engaging one end of the blank and the other engaging the opposite end of the blank at two separated points to determine the orientation of the blank, means for positively operating one of the positioning means to translate the blank while the other positioning means is held yieldingly against the blank, and means for clamping the blank during operation of the operating means.

96. In a machine of the class described, the combination of means for performing in succession a plurality of stock removing operations upon a heel, and means for expelling the heel after the final shaping operation including means in which energy is stored while the machine is operating and released after the operations are finished.

97. In a machine of the class described, the combination of means for performing automatically a plurality of stock removing operations upon successive heels, and power operated means for effecting removal of the heel from the machine comprising means in which energy is stored during operation of the machine and released after the operations on the heel have been concluded.

98. In a machine of the class described, an endless carrier for unattached heels, means for operating upon the heels when brought by the carrier to one location, and automatic means for breasting the heels when brought by movement of the carrier to another location.

99. In a machine for finishing unattached heels, the combination of a magazine serving as a source of supply of heel blanks, means for performing a series of operations upon the heel blanks, and automatic means for receiving heel blanks successively from the magazine and presenting the same to said first-named means.

100. In a machine for operating on heels, a conveyor movable intermittently in a horizontal plane and having a plurality of heel carriers, a spring-actuated heel clamp

for each of the carriers, and automatic means for lifting each clamp in turn at one dwell of the conveyor and for placing a heel on the carrier.

101. An organized machine for use in making heels comprising, in combination, a rotary turret carrying a plurality of heel holders, a heel clamp for each holder, a plurality of means for operating on heels presented by the holders, automatic means for causing the clamps to hold the heels on the holders, and mechanism to operate the turret intermittently to present heels sequentially to the operating means.

102. In a machine of the class described, a rotatable heel carrier provided with a plurality of heel clamping devices, means for intermittently rotating said carrier and stopping the same with two or more of its clamping devices adjacent to stations, means for breasting a heel adjacent to one of said stations, and means adjacent to another station for automatically releasing a clamping device to allow removal of a breasted heel and insertion of an unbreasted heel, said device being arranged automatically to clamp the fed heel prior to its arrival at the breasting station.

103. In a heel breasting machine, means for breasting a heel, a rotatable heel carrier, a plurality of spring-operated heel clamping devices arranged on the carrier to apply heightwise pressure to the heels, means for rotating the carrier to present the clamped heels in operative relation to the breasting means and intermittently stopping the carrier at a feeding station, and automatic means operated by movement of the carrier for releasing the clamps in turn to permit removal of the heel and introduction of a fresh heel and for clamping the fresh heel to hold it on the carrier during the operation of the breasting means.

104. In a heel breasting machine, a breasting knife, a rotatable table, a plurality of individual heel clamps mounted on the table and arranged to apply spring pressure heightwise of the heels, and a stationary cam for releasing the clamps to permit feeding of heels to the clamps and removal of breasted heels.

105. In a machine of the class described, the combination of a plurality of blank carriers arranged for intermittent movement, a plurality of operating means located at various positions of rest of the carriers for operating upon the blanks, a magazine for blanks, and mechanism for transferring a blank from the magazine and locating the blank in predetermined position on each of the carriers as they are presented in turn.

106. In a machine of the class described, the combination of a plurality of blank carriers arranged for intermittent movement, a

- plurality of operating means located at various positions of rest of the carriers for operating on the blanks, a magazine for blanks, and mechanism for taking a blank from the magazine, determining its position of orientation and presenting the blank on a carrier in positively determined longitudinal position.
107. In a machine of the class described, the combination of a plurality of blank carriers arranged for intermittent movement in a horizontal plane, a plurality of operating means located at various positions of rest of the carriers for operating on the blanks, a magazine for blanks, and mechanism for taking a blank from the magazine, determining its position of rotation about a vertical axis passing through the blank and presenting the blank on the carrier in positively determined longitudinal position.
108. In a machine of the class described, the combination of a plurality of blank carriers arranged for intermittent movement, a plurality of operating means located at various positions of rest of the carriers for operating upon the blanks, a magazine for blanks, and automatic mechanism for transferring a blank from the magazine and locating the blank in predetermined position on one of the carriers, a blank being transferred to each of the carriers as they are presented in turn.
109. In a machine for treating unattached shoe bottom blanks, a series of blank supports constructed and arranged for intermittent rotation in a horizontal plane, a series of blank treating mechanisms arranged along the path of movement of the supports and operating to treat blanks on the supports during the dwells in their rotation, a magazine for blanks, and mechanism operating during each dwell of the supports to remove a blank from the magazine and present it in predetermined position on one of the supports.
110. In a machine for treating shoe bottom blanks, the combination of a magazine for holding the blanks in feeding position, blank treating means located in a position remote from the feeding position, blank feeding means acting to slide the bottom blank from the magazine and present it in predetermined fed position, and a rotary transerrer acting to carry the fed blank to the blank treating means.
111. In a machine for operating on unattached shoe bottom blanks, a blank support, means for presenting a blank on the support, means for moving the support in a horizontal plane through a plurality of positions at which operations are performed on the supported blank, a member movable into engagement with the blank to clamp it to the support, and means situated at different positions of the support for controlling the engagement of the clamping means with the blank and its release therefrom.
112. In a machine for operating on unattached shoe bottom blanks, a blank support, automatic means for presenting a blank in position on the support, means for moving the support through a plurality of positions at which operations are performed on the supported blank, a member movable into engagement with the blank to clamp it to the support, and means situated at different positions of the support for controlling the engagement of the clamping member with the blank and its release therefrom.
113. In a machine for treating unattached heels, the combination of heel blank delivery means, a series of tools for performing separate operations upon heel blanks, and an automatically controlled conveyor to receive heel blanks from the delivery means and present them sequentially to the tools.
114. In a machine for operating upon heels, the combination of a conveyor arranged to pass a series of operating stations, a series of heel holders mounted therein, automatic means for placing the heels in the heel holders, and means at each station to operate upon the successive heels presented thereto.
115. A machine for preparing unattached heels comprising, in combination, a plurality of reciprocating knives, and means for automatically presenting a succession of heels sequentially to said knives to be operated upon thereby, the longitudinal median plane of each presented heel being parallel to the direction of reciprocation of each knife.
116. A machine for preparing unattached heels comprising, in combination, a plurality of reciprocating knives, and means including a magazine, a pusher and a heel support for presenting a succession of heels sequentially to said knives to be operated on thereby.
117. A machine for preparing unattached heels comprising, in combination, a magazine, means for removing heels successively from the magazine and presenting them intermittently in spaced localities to be operated upon, and a plurality of spaced reciprocating knives adjacent said localities to operate on heels so presented to make a plurality of cuts on each heel.
118. A machine for preparing unattached heels comprising, in combination, a plurality of simultaneously movable cutters, and means for automatically presenting a succession of unattached heels sequentially thereto so that a plurality of heels are operated upon simultaneously by the cutters and so that each heel is operated upon successively by the cutters, the direction of movement of each cutter with respect to the heel being parallel to the longitudinal median plane of the heel.

119. A machine for preparing unattached heels comprising, in combination, members yieldingly to engage the tread and seat surfaces of a heel, means for pushing heels between said members, mechanism for automatically advancing the heels past a plurality of operating stations, and a reciprocating knife opposite each station to operate successively on the heels.
120. A machine for preparing unattached heels comprising, in combination, a plurality of cutters at spaced localities, feeding and supporting means successively to present heels sequentially at said localities, and mechanism for relatively moving said means and the cutters to cause the cutters successively to remove stock from each heel.
121. In a machine of the class described, a plurality of cutters each adapted for operation upon the breast of a heel, a carrier, and means for moving the carrier first to a position for operation of one cutter upon the heel breast and then into position for operation of the other cutter on the heel breast upon relative movement of the carrier and said other cutter.

In testimony whereof I have signed my name to this specification.

LOUIS A. CASGRAIN.
